UNITED STATES PATENT OFFICE.

WILLIAM VARNEY, OF NEW YORK, N. Y.

DESIGN FOR A CANDLESTICK.

SPECIFICATION forming part of Design No. 24,401, dated June 18, 1895.

Application filed May 9, 1895. Serial No. 548,770. Term of patent 3½ years.

To all whom it may concern:

Be it known that I, WILLIAM VARNEY, a citizen of the United States, residing at New York city, in the county and State of New York, have invented and produced a new and original Design for a Candlestick, of which the following is a specification, reference being had to the accompanying drawing, forming a part thereof, in which is represented a perspective view of a candlestick in which the new design is embodied.

The leading feature of the design consists of the representation of a flower and a cup

somewhat concealed among the leaves, together with a foliage support. The minor features appear in the support, which apparently comprises stems, leaves and buds arranged to appear as the base of the candlestick.

I claim—

The design for a candlestick, substantially as herein shown and described.

WILLIAM VARNEY.
